RUG FILLER HOLDER

Romeo Paulus, Plainville, Mass.

Application January 15, 1942, Serial No. 426,803

6 Claims. (Cl. 242—146)

The present invention relates to a means and method of unwinding yarn fillers and more particularly to the fillers which are used in certain types of rug manufacture.

These fillers for the most part as they come from the calender and condensing machines are composed of loosely held fibers, some of which may be very short, so that the filler has very little strength of its own to resist breakage of the strands. For various types of rug manufacture, the filler as it comes from the condensing machine, may be an eighth of an inch or more in diameter, with such a low resistance to separation, that even its own weight will be sufficient to cause the strand to break. Such strands as they come from the machine are rolled up into balls, some of which may be as great as two feet in diameter and a foot high, the ball being rolled up in the usual way such that when it is unwound and fed into the machine where it is used, it is consumed from the inside of the cylindrical ball outward. The order of unwinding these big balls, is that the inner turns are taken off up and down the cylinder, making the cylindrical ball hollow until gradually even outside turns are used up.

The unwinding of these balls progresses satisfactorily while most of the center portion of the ball is being used up, but when the strands of the outer ball are being used up, the ball usually collapses and some of the turns are apt to snare up when they are being fed from the lower turns of the ball. In other words, when the ball begins to collapse the top turns fall over the turns underneath and in practically all cases unless special precautions are taken to see this does not happen, the strand is sure to pull apart.

In the present invention this difficulty is overcome and means are automatically provided whereby the entire ball may be used up without in any way touching or arranging the ball at any time.

In the present invention the ball falls apart in such a way that the turns remain uniformly supported so that the yarn at all times may be drawn whether it is the bottom layer or some other turns nearer the top of the pile.

The method by which this unwinding of the ball is accomplished will be more clearly understood from the description given in the specification below when taken in connection with the drawing, in which:

Figure 1 shows a section in elevation through the center of the container in which the yarn cylinder is placed.

Figure 2 shows a plan view of the device shown in Figure 1.

Figure 3 shows an elevation of the device with the ball or cylinder of yarn in place.

Figure 4 shows a top view looking down at the top of Figure 3.

Figure 5 shows a view similar to Figure 3 with the ball of yarn partially used up, and,

Figure 6 shows a plan view of the condition shown in Figure 5.

The container itself is extremely simple in design. It comprises a base member 1 which as shown in Figure 1 has a V shaped central section with open straight sides 2 and 3 which are preferably parallel, and end walls 4 and 5 of metal or other suitable material, which end walls form segments of arcs as indicated more clearly in Figure 2 wherein the center line 0—0 parallel to the sides 2 and 3 is a diameter of the circle upon which the walls 4 and 5 are formed. As indicated more clearly in Figure 1 these side elements 4 and 5 are inclined at a slight angle approximately 10° or somewhat less so as to make the lower end of the container slightly smaller in diameter than the upper end. The V shaped base element 1 has sloping sides inclined upwards from the center axis 6 perpendicular to the sides of the base 2 and 3. While the open ends at 2 and 3 may if desired, be closed in a broad frame extending in an arc substantially bigger and further out than the arcs 4 and 5, it is more desirable to leave the sides 2 and 3 open provided nothing will interfere with the arrangement which the cylindrical ball will naturally take. In the present invention the ball is placed as indicated in Figures 3 and 4 when it is completely full.

It will be noted from these figures that the cylindrical ball 7, when full, rests substantially only at the upper corners 8 and 9 of the inclined surfaces 10 and 11 respectively of the base member 1. The ball itself is sufficiently yielding so that it will rest uniformly within the arched sides 4 and 5 of the container. The ball is wound in such a way (as indicated more clearly in Figure 4) so that it may be unwound from the center turns 12.

It will be evident from consideration of Figures 3 and 4 that the ball will hold its position in the frame while the inner portion of the cylinder is used up. It is only when the inside hole has a diameter extending approximately to the turn marked A that the ball begins to fall apart. As it falls apart it assumes a position generally indicated in Figures 5 and 6.

In its unwinding as the ball is used up from this point, the lower turns of the ball begin to slide inward along the inclines 10 and 11 at the same time that the upper turns fall outward at the sides of the frame. The inner lower turns in this way become elongated into an elliptical shape lying crosswise at the bottom of the frame, while the outer top turns of the cylinder of Figures 3 and 4, substantially maintain their form, gradually lowering their position towards the base of the frame, but resting against the side walls of the frame. In Figure 6, therefore, the turns which are more nearly elliptical as for instance the turns 12' are at the lower side of the ball as the ball collapses, but act to keep successive layers of yarn in their original relationship preventing any snarling right up to the end of the ball. When the yarn cylinder collapses therefore, the bottom supporting turns which contact the base of the frame only in the corners leaving the inclined surfaces entirely exposed, begin to edge slightly inward toward the vertex of the base, and support together with the sides, the weak ball with its turns in substantially the same relationship. The base is only partly covered. The ball or cylinder will therefore be completely used up without danger of the yarn breaking.

It will be understood from the description given that the construction of the frame may be slightly varied dependent upon the size and shape of the ball. In all cases however the purposes of the construction is such as to make the inner turns when the cylinder disintegrates always feed in the same consecutive order until the yarn is used up.

Various size frames must of course be used to accommodate the various sizes of rolls, the general distinguishing feature being that the walls are sloped inwardly downward with a base with an inclined slope so that the ball or roll will fall apart and disintegrate in the correct manner.

Having now described my invention, I claim:

1. A frame for holding a cylindrical ball of yarn filler which is unwound from the inner turns outward, said frame comprising a base member having plane surfaces sloped downward to a common center line, the outer peripheral edge of the base member being in the shape of an arc of a circle, and end wall members attached to the base at said peripheral edge, said end wall members being inclined outwardly at a slight

angle and of a size adapted to support the cylindrical surface of the ball.

2. A holder for holding cylindrical balls of yarn fillers wherein the yarn is to be unwound from the inside layers outward, comprising an open frame having curved walls in which the ball is adapted to fit with the cylindrical surface of the ball touching the curved walls, a base supporting said walls having a surface inclined from the edges supporting said walls to the central portion of said base.

3. A holder for holding cylindrical balls of yarn fillers wherein the yarn is to be unwound from the inside layers outward, comprising an open frame having walls shaped to fit the cylindrical surface of the ball at the top of the walls and tapering inwardly towards the bottom of the walls and a base supporting said walls having surfaces inclined towards a central section of the base.

4. A holder for holding cylindrical balls of yarn fillers wherein the yarn filler is to be unwound from the inside layers outward comprising an open frame having inclined side walls with a curved inner surface, a base member supporting said side walls, said base member having plane surfaces inclined downwardly from the edges where they are joined to said walls.

5. A holder for holding cylindrical balls of yarn fillers wherein the yarn is to be unwound from the inside layers outward comprising an open frame having an elongated base with arcuate end sections, a pair of side walls joined to said end sections having a similar curved shape and extending upwards from said base at a slightly outwardly inclined angle, said base having surfaces inclined downward from the edges at which said walls are joined towards an intersecting central portion.

6. A holder for holding cylindrical balls of yarn wherein the yarn is to be unwound from the inside layer outward comprising an open frame having an elongated base member with convex end sections, said base having surfaces sloped upwards from a central section to the convex edges of the base, side walls having a convex shape joined to the base at the convex ends thereof, said side walls extending upwardly and slightly inclined outwardly and adapted to receive the cylindrical balls of said yarn filler.

ROMEOPAULUS.
